UNITED STATES PATENT OFFICE.

EDMUND T. FLYNN, OF CAMBRIDGE, MASSACHUSETTS, ASSIGNOR TO CAMBRIDGE
REVERSIBLE LIFE FLOAT, INC., OF BOSTON, MASSACHUSETTS, A CORPORATION
OF MASSACHUSETTS.

LIFE-RAFT.

1,272,412.

Specification of Letters Patent.

Patented July 16, 1918.

Application filed March 16, 1918. Serial No. 222,976.

To all whom it may concern:

Be it known that I, EDMUND T. FLYNN, of Cambridge, in the county of Middlesex and State of Massachusetts, have invented a new and useful Life-Raft, of which the following is a specification.

A feature of my invention is that my raft is substantially pointed at both ends, and therefore is easily propelled or towed, this not having been heretofore done because of the nature of the structure of the buoyant member.

Another feature of my invention is that the buoyant member is non-circular in cross-section, which, among other advantages, increases the strength.

Another feature is the use of wood, preferably bass-wood or balsa, as a part of the buoyant member, and this gives substantial rigidity and durability as well as buoyancy particularly when the corner pieces are used in the particular combination shown, the wood also acting as an efficient buffer for the metal shell.

Another feature is the inner metal shell made of two pieces and particularly the joints thereof which extend lengthwise and give reinforcement.

Another feature is the metal band to encircle and strengthen the buoyant member.

Another feature is a storage receptacle for supplies, food, water and other things located in the buoyant member itself and accessible from both sides, my raft being reversible. The cover for the receptacle is also a feature of my invention, particularly because of its waterproof quality and of its easy removability.

Another feature is the diagonal arrangement of slats for the platform.

Other features will be pointed out below.

In the drawings

Figure 1 is a plan of a life-raft embodying my invention;

Fig. 2 is an elevation of the same;

Fig. 3 is a section on line 3—3 of Fig. 1 but on a larger scale;

Fig. 4 is a section on the line 4—4 of Fig. 1 but on a larger scale; and

Fig. 5 is a section on line 5—5 of Fig. 4.

The buoyant or float member A of my life-raft is pointed at the ends a and a' and comprises an internal hollow metal shell or

polygonal tube B, which consists of two parts b and b' each running lengthwise entirely around the device, and each having a longitudinal flange at one edge bent to form three parallel longitudinal walls while at the other edge each part has a longitudinal flange bent to form two parallel longitudinal walls, the two walls of part b coöperating with the three walls of part b' and vice versa, the coöperating walls being soldered together and riveted as at b² and b³, this construction giving a very powerful reinforcement to the metal shell.

Outside of the metal I provide strips or planks b⁴, b⁵ and b⁶ of wood, preferably bass-wood or balsa, extending longitudinally of the device and along the pointed edges, the strips which are adjacent longitudinally being suitably mitered.

The strips b⁵ fit closely to the flanged walls of the metal parts and the strips b⁶ are pointed as shown.

These wooden strips preserve their buoyancy much longer than material heretofore used. They act much more efficiently than anything heretofore used as a buffer for the metal shell and they permit the use of pointed ends of the raft because the wood can be shaped for that purpose. Moreover, the chief strain in my device comes on the wood and not on the metal.

Canvas D is wrapped around the food, the canvas and the wood, and particularly the pointed pieces coöperating to make a particularly rigid but buoyant construction.

At intervals outside of the canvas I provide flat metal bands d d which are flanged at d', these flanges having between them split washers d² and being held together by rivets d³. These bands press slightly into the canvas so that they are held against slipping. The bands may be made of galvanized iron or other suitable material and each has a loop or arm d⁴ welded to it.

The metal shell is divided into a series of compartments by metal plates E which fit exactly the polygonal interior of the metal shell and may be soldered thereto, the great advantage of this construction being that if one portion of the device should be punctured or otherwise damaged the structure as a whole will still remain buoyant.

I use two of the compartments E' and E².

as receptacles for food and supplies such as medical equipment, water and rockets. Access to compartment E' is illustrated in Fig. 4, access to compartment E² being similar. The metal parts are cut away to leave flanges e and e'. Metal pieces e² and e³ rest on these flanges and are bent over and secured by screws e⁴ and e⁵ to the wooden pieces b⁶. Riveted to the flanges e and e' is the neck piece E³ which is oval in shape and which is provided with shelves e⁶ and e⁷. Along the top of the neck I place gasket e⁸ and on that rests cover F grooved on its inner side to tightly engage the gasket, the cover being perforated to receive shank f which has at one end nut f' which nut engages inside of locking member f², the latter normally engaging shelves e⁶ and e⁷, said shank being threaded at its opposite end for engagement with wing nut f³ which may be rotated to firmly clamp the cover F in position. I preferably provide an additional gasket f⁴ in the outer face of the cover in engagement with the wing nut. When it is desired to gain access to compartment E' the wing nut is loosened and the locking member is turned out of engagement with the shelves, whereupon the cover may be readily removed. I thus provide access to the interior of the buoyant member but at the same time make said interior normally water tight.

Access to compartment E' may also be had through lower neck piece E⁴, it being understood that my buoyant member is reversible.

The platform consists of slats g and g' running along the edges and between them are fastened transverse slats g² while I also provide diagonal slats g³ above the transverse slats and diagonal slats g⁴ below the transverse slats, the diagonal slats being suitably connected to the transverse slats, this construction being very efficient, because, among other reasons, each diagonal slat distributes weight among a number of transverse slats.

At intervals, preferably corresponding with the spaces between the metal bands above described, I attach metal loops H to slats g and g' by bolts h, one flange of the loop being above and other below the platform.

Wire ropes J are looped through loops H and inner loops or arms d⁴ and thus support the platform. I prefer also to give additional strength by using the diagonal cords or wires J', each diagonal cord running from the upper loop of one wire rope J to the lower loop of the adjacent wire rope J.

Cord K runs along the outside of the buoyant member and is looped around the outer arm d⁴ and between said arms carries the floats k.

It will be clear that a great advantage of my polygonal metal shell is that I may use

with it wood which will be very strong and very cheap and will give reinforcement.

My polygonal structure also has the advantage of permitting a substantially pointed end for the device, it being practically impossible to provide a pointed end if a circular metal shell is used.

Among the advantages of my raft I may point out that it is very durable as it will preserve its buoyant properties indefinitely, it is very strong and it is very serviceable.

I prefer to connect the adjacent mitered metal shell pieces by solder but of course other connecting means might be used depending upon circumstances.

What I claim is:

1. A life raft comprising a metal shell which is polygonal in cross-section; and a buoyant member made of wood outside of said shell.

2. A life raft comprising a metal shell which is polygonal in cross-section; and a buoyant member outside of said shell.

3. A life raft comprising an inner hollow member made of metal and being polygonal in cross-section; bass-wood surrounding and reinforcing said hollow member; and means for holding the metal member and said wood together.

4. A life raft comprising a hollow metal shell which is polygonal in cross-section; strips of wood rectangular in cross-section; strips of wood triangular in cross-section; canvas surrounding said strips and coöperating with them to form a substantially rigid but buoyant cover for the metal shell.

5. A life raft comprising a metal shell; buoyant material; a metal band to hold said material to said shell; said band having an arm welded thereto; a platform; and means connecting said platform and said arm.

6. A life raft comprising a metal shell made in two parts, each part having a flange extending longitudinally of the device; and means to hold said flanges together.

7. A life raft comprising a metal shell made in two parts, one part having a flange with three parallel walls and the other having a flange with two parallel walls, the walls of one part engaging the walls of the other part; and means to hold said walls together.

8. A life raft comprising a metal shell having longitudinally extending flanges; strips of wood extending longitudinally of the device; and means to hold said strips in engagement with said flanges.

9. A life raft comprising a metal shell having an opening; buoyant material covering said shell and having an opening in line with the opening in said shell; and means normally closing the opening in said shell but removable to permit access to the interior of said shell through said openings.

10. A life raft comprising a hollow metal

shell; buoyant material covering said shell; an opening in said shell leading to the interior thereof; a cover for said opening; and means to hold said cover in position.

5 11. A life raft comprising buoyant material; a hollow metal shell within said buoyant material; a neck leading into said shell

and provided with a shelf; a locking member to engage said shelf; a cover for said neck and controlling access to the interior 10 of said shell; and means coöperating with the locking member to hold said cover in position with relation to said neck.

EDMUND T. FLYNN.
